UNITED STATES PATENT OFFICE.

WALTER ERBSLÖH, OF BARMEN, GERMANY.

ROLLING-MACHINE.

1,226,198.

Specification of Letters Patent. Patented May 15, 1917.

Application filed May 14, 1913. Serial No. 767,661.

To all whom it may concern:

Be it known that I, WALTER ERBSLÖH, of Barmen, Schoenenstrasse 1, Rhenish Prussia, Germany, a subject of the Emperor of Germany, have invented new and useful Improvements in Rolling - Machines, of which the following is a specification.

My invention pertains to rolling machines and particularly to that class of machines in which reversed rollers are employed. It consists in applying two drums, one on each side of the machine, so that the blank or strip may travel or reciprocate between the drums and pass through the rolls until the desired thickness is obtained, in arranging a clutch or coupling and a brake for each drum and in providing cooling means for the surface of the rolls to permit a continuous operation of the device without wear and tear.

My invention is fully shown on the accompanying drawings on which—

Figure 1 is a side elevation of the complete machine.

Fig. 2 is a plan of the machine.

Fig. 3 shows the working rolls from the side provided with cooling means.

Fig. 4 is a similar view of a modified arrangement.

Fig. 5 shows another modification of the cooling construction and

Fig. 6 is a longitudinal view of the rolls.

1 is the base plate of the machine carrying a standard 2 in which are journaled the rolls 3, 4 which are pressed together by a known contrivance 5. 6 is the metal blank or band of aluminium which is to be rolled out in endless strips of thin dimensions and which according to my invention travels to and fro between two drums 7, 8 on which the material is wound under strong tension, the rolls 3 and 4 changing their rotation accordingly with each stroke. The arrangement for reversing the said rolls 3, 4, is known and not part of my invention.

On both sides of the rolls 3, 4, is placed a pressing device 10 consisting of a supporting or lower and of a movable or upper die 10^a and 10^b and a pressing handle 10^c. This device serves also for guiding the blanks or strips in the prescribed position and to facilitate the entrance of the blank or strip between the rolls 3, 4. For driving the roll 3 the following means are provided. On the motor or main shaft 11 is mounted a gear 12 meshing with a wheel 13 keyed to a shaft

14, said shaft carrying a gear 15. This gear is in mesh with a wheel 16 forming part of a shaft 17, on which is also keyed a gear 18, that is in mesh with a gear wheel 19 and this wheel is fastened on the shaft of roller 3. For revolving said roller in the contrary direction the shafts 14, 17 carry the gears 15^a and 16^a and the couplings x , x^1 respectively extend from the wheels 16 and 16^a as shown in Fig. 2. Shaft 17 is fitted with a pulley 21 which transmits motion by means of a belt 21^b to a pulley 22 fitting loosely on a shaft 23, that is journaled in bearings 27. On the extreme end of this shaft is placed a pinion 24 meshing with a gear wheel 25, which is keyed on a shaft 26 that carries the drum 8. As will be easily understood by the foregoing the drum is revolved by the gear shown and described. The drum 7 on the left side of the standard 2 is revolved in similar manner by the pinion 18^a driven from the wheel 19 and mounted on a shaft 17^a the pulleys 21^a, 22^a, belt 21^b, and the gear wheels 24^a, 25^a the latter being mounted on shaft 26^a which is guided in the bearings 27^a.

According to the reversed rotation of the rolls 3, 4 the drums 7 and 8 have to change rotation and the driving means of one drum are put out of action or interrupted when the blank or strip is passed through the rolls 3, 4 and wound up on the free or empty drum, in which case of course the coacting drum is free to rotate to allow the blank or strip to be drawn off. For this purpose the shafts 26 and 26^a of the drums 7 and 8 which change their rotation are coupled with the shafts 28, 23^a, the pulleys 22, 22^a of which move in opposite directions. This is effected in the present example by means of a spring coupling being advantageously adapted for the purpose of suddenly reversing the different shafts as will be understood from the following:

The pulley 22 is provided with a hub 29 around which is placed a coiled spring 30 which is connected with said pulley 22 and bears on a disk 31 which rotates with shaft 23 and may at the same time be moved thereupon to and fro. If now said disk 31 is moved by means of a lever 32 toward the pulley 22, the spring is pressed together, its length is shortened and it is strongly pressed on the hub 29 so that shafts 23 and 26 respectively are caused to revolve and the drum 8 to wind up the blank or strip. The

winding of the blank or strip on the drum 8 is therefore effected in a correct manner without formation of folds or breakage of the edges. After the blank has passed the drum 8, the pulley 22 will be put out of action by moving the disk 31 out of engagement therewith, by means of the lever 32. At the same time pulley 22^a will be put into operation by movement of the lever 32^a, said lever 32^a coöperating with the shaft 23^a by the members 29^a, 30^a, and 31^a, in a manner similar to the way in which the pulley 22 coöperates with the shaft 23 by the corresponding members 29, 30, 31, and 32, as hereinbefore described. The drum 7 is thus caused to revolve with the result that the drums 3 and 4, through which the blank is now passing, are moved in an opposite direction. In order that the speed of rotation of the drum 8 may be regulated, each drum is fitted with a brake, comprising a disk 33, 33^a respectively, a weighted lever 35, 35^a and a brake block 34, 34^a bearing on the disk 33, 33^a. It will be also clear that in the operation of the new machine the blank can travel constantly or reciprocate between the drums 7 and 8 and pass the rolls 3, 4 until it is rolled out to the desired thickness without being taken off from one of the drums and in consequence thereof much time is saved and a strip or band is obtained with smooth edges. In obtaining such an effect it is however supposed that the rolls are cooled on their surface in order to prevent the same from getting too much heated resulting from the constant revolution.

In Fig. 6 I have shown a longitudinal view of the rolls, and from this figure it will be clearly understood that the rolls are constructed to provide a substantially horizontal surface for the entrance of a blank, owing to the extreme pressure exerted on said rolls, at the time of the entrance of the blank.

In Fig. 3 I have disclosed a construction according to which the rolls are cooled with fresh air, which is thrown by means of tubes 36, 37 upon the roll surface. Prefer-

ably the tubes are fitted at their ends with nozzles and connected with a fan, (not shown in the drawing) and it will be clear that the constant air stream will sufficiently cool the surface of the rolls. While I have described the cooling medium as air, it is of course apparent that I may employ liquid, air, water, chemicals, or the like, and if the blank under treatment requires heating, I may of course employ a heating medium in combination with my cooling apparatus.

The modification of Fig. 3 is illustrated in Fig. 4 which consists of chambers 38 and 39 attached to the rolls as shown. The chambers 38 and 39 have perforations in the inner walls thereof, the layer 40 of asbestos being inserted between the chambers and rolls. The cooling means is admitted by tubings 41 and the escape of said cooling means is through tubings 42.

Finally in Fig. 5 is shown a combination of inner and outer cooling, the chambers 38, 39 or the tubes 36, 37 being connected with tubes 43, 44 and 45 which enter the center of the rollers as shown in Fig. 5.

What I claim as my invention and desire to secure by Letters Patent is:—

1. In a metal rolling machine, a frame, standards on the frame, pressing rolls carried by the standards, a drum at each end of the frame, gearing for operating the drums, clutch members for moving the drums into and out of operation, whereby the direction of rotation of the drums and rolls is reversed.

2. In a metal rolling machine, a frame, standards supported centrally of the frame, pressing rolls supported by the standards, a drum supported at each end of the frame, and on the same horizontal plane with the pressing rolls, means for operating the drums, means for communicating movement of the drums to the pressing rolls, and clutch members for throwing the drums into and out of operation.
